MACHINE FOR TESTING TENSILE, COM-
PRESSIVE, BENDING, SHEARING, ETC.,
STRENGTH OF METALS OR OTHER MATE-
RIALS

Albert René Arthuis, Paris, France

Application September 13, 1946, Serial No. 696,676
In France June 26, 1946

1 Claim. (Cl. 73—93)

1 The present invention relates to a machine for testing tensile, compressive, bending, shearing, etc. strength of metals or other materials, without any other modification on said machine than the change of the tools which are intended to act upon the test samples.

This machine is characterized by the fact that a dynamometric apparatus is hydraulically coupled with a press in order to allow the reading of the stresses being made upon a dial and, at the same time, to obtain the diagrams of the stresses and of the distortions to which the test samples are subjected. The two pistons in question, one of the press, the other of the dynamometric apparatus or differential piston, take up simultaneously the same pressure supplied by a pump.

The dynamometric apparatus is further characterized by the fact that it enables the modification of the sensitiveness of the machine by means of suppression or adjunction of one or a plurality of springs which are controlled by the differential piston, and by the adjustment of an abutment which retains said springs.

Another feature of the invention enables the machine to extend its scope of action, by adding to the machine a whole range of sensitivities which are achieved no longer through the single modification of the strength of the dynamometer springs, but conjointly through a modification of the active area of the press piston.

In order to attain that purpose the invention uses a plurality of telescopic pistons, that of the greatest size bearing or constituting the cylinder of that of the immediate smaller area, which latter contains the following piston, and so on. With this arrangement, it becomes possible to let act the main piston which provides the greatest stress or to make the latter immovable, which becomes then the cylinder of the piston of lesser area, or further to make the two prior immovable, whilst a third piston acts alone and so on.

The stresses being a direct function of the cross-sections, if for instance the various pistons are at the ratio $1:6$, the maximum stress which may be exerted by each piston of the series will be $\frac{1}{6}$, $\frac{1}{36}$ etc. of the stress which the main piston is able to exert.

With that device, the same relative accuracy is preserved, since the dynamometer is still affected by the pressure given by the pump; for that reason, its springs, regardless of the piston used, will always require the same pressure in order to attain their same maximum compression.

2 The number of the sensitivities becomes therefore equal to the number of combinations which are performable by the lot of the dynamometer springs, multiplied by the number of pistons acting upon the samples being tested.

Of course, the dial of the dynamometer is provided with graduated scales equal in number to that of possible combinations, the maximum amplitude of the needle giving in any case the maximum stress of the combination which has been chosen.

Fig. 1 is an elevation with a partial cross-section of the machine as mounted for a tension test.

Fig. 2 shows the fitting for a compression test with the aid of a ball.

Fig. 3 is an enlarged view with a half cross-section and half elevation of the dynamometric apparatus.

Fig. 4 is a partial side view of Fig. 3.

Fig. 5 shows an enlarged vertical cross-section of the arrangement of the telescopic pistons which permits to obtain six different sensitivities in conjunction with the dynamometric device.

The machine comprises a press 1 with its piston 2 which is adjusted without any intermediate tightening member in a cylinder 3 forming also a container.

To that press is secured by means of a lug 4 the dynamometric apparatus which comprises a second unit such as a piston 5 and a cylinder 6 of a lesser size and connected to the cylinder 3 by a conduit 7.

A screw 11 passes through a head 12 set above the piston 2 and the vertical motion is performed without rotation by means of the wheel 13 acting as a nut.

A pump 8 acts at the same time upon the lower faces of pistons 2 and 5. The piston 2 acts upon the test sample E, secured between the clamps 9 and 10, and the other piston 5 acts upon one or a plurality of springs R and R' of the dynamometric apparatus.

The dynamometric apparatus is provided both with a dial for reading and a recording device.

The stresses are read upon the dial 14 over which moves a needle which is controlled by a roller 29 connected to the differential piston 5 by the medium of a cable C.

The recording device is of the drum type. The device 15 is controlled by the vertical motion of the piston 2 and is connected therewith by the medium of a support 16 carried by the piston 2, a roller 17 and a cable 18 extended between

the piston 2 and the recording device 15. A marking device 19 is vertically moved through the motion of the differential piston 5, which carries a finger 20 gliding within a groove 20' and controlling a cable 21 which passes around an amplifying wheel 22 and which is connected with the marking device 19.

The marking device is guided within the guide 23. The free end of cable 18 which drives the drum 15 is either secured to a spring or is stretched by a weight 24.

The dynamometric apparatus is completed by a device allowing the modification of the sensitiveness of the stresses. It comprises a hollow sleeve 25 movable within a head 26 which both serve as abutments for springs R, R', the sleeve being able to be stopped by a locking device 27. A spring 28 is intended to maintain the sleeve 25 in its upper position when it is not locked.

The operation is as follows: the test samples E being suitably shaped for the test to be performed are clamped at the same time by a clamp 9 secured to the main piston 2 and by a clamp 10 secured to the screw 11, said screw serving to vary the distance between the clamps in accordance with the size of the samples to be tested.

The pump 8 being set in movement an increasing pressure is exerted in the two cylinders 3 and 6. The piston 2 being pushed in vertical direction (assuming that a tensile test is to be performed), the upper clamp 9 which is made integral with said piston tends to go away from the clamp 10 and exerts therefore upon the sample a tensile stress which increases up to breaking of the same.

The differential piston 5 is simultaneously also subjected to a vertical pressure and compresses the spring R, or the two springs R and R', the purpose being to give the piston a stroke which is at a direct ratio with the pressure exerted within the two cylinders and therefore with the stress to which the test sample is subjected. This stress may thus be indicated upon the dial 14 by a needle which amplifies the stroke of piston 5, since it is coupled with the latter by means of cable C passing around the roller 29 which is secured to the axis of the needle.

When the two springs R, R' are in operation, the maximum course of piston 5 is only attained for the maximum power of the machine but the spring R' may be made free by raising the sleeve 25 to a height slightly above the maximum stroke of the piston.

This stroke corresponds then only to a fraction of the maximum power of the machine, which gives the latter a greater sensitiveness. A combination of three or four springs, instead of two, may provide a greater number of sensitivities by letting it in operation separately or in groups. Upon the dial is a number of graduations corresponding to that of the various sensitivities.

Accordingly to the Fig. 5, the sensitivities may be increased by the modification of the press piston. In this arrangement 3 is the main cylinder enclosing its piston 2 which is provided inwardly with a cylinder 30 formed integral therewith wherein slides a piston 31 the hollowed and bored center of which constitutes the cylinder for a piston 32. The lower part of cylinder 30 is provided with a central channel 34 which discharges into the lower part of piston 2 and sets constantly in communication the cylinders 3, 30 and 31.

The upper flange of piston 2 affords two holes

35 which enables the latter to be made integral with the body of the machine by means of two screw threaded studs 36.

The piston 31 may further be made integral with its cylinder 30 by the medium of two grub screws 37 overlapping the junction of the two parts or otherwise.

Conduits and gutters 38 and 39 are provided at different places for discharging the oil which ensures automatically the lubrication. Finally, the upper part of piston 32 affords a cavity 40 which receives the centering disc of different apparatus.

The operation is the following:

1. In order to achieve great stresses the piston 2 is made free of the machine body by unscrewing the nuts of the studs 36—in the position of the drawings—and the assembly operates at the same manner as when the piston 2 would not contain any inner member.

2. In order to obtain mean stresses, the piston 2 is made unmovable and the grub screws 37 are removed. In that case the pressure acts only upon the section of piston 31.

3. In order to perform the smallest stresses the piston 2 is made unmovable as is also the piston 31. In that case, the pressure acts only upon the section of piston 32.

The diagrams are obtained by the horizontal motion of the paper wound around the drum 15 which is driven by the movement of the piston used, in correspondence with the elongations or distortions of the test samples, and by the vertical displacement upon the same paper of the marking device 19 which is raised through the medium of the double stepped pulley 22, which has the purpose of amplifying the motion of the differential piston 5.

Having thus described my invention I claim:

A machine for testing the strength and distortion of test samples of metals and other materials, having a hydraulic main press having a cylinder, and a stress-exerting piston of variable active cross-section, said machine comprising, in combination, a dynamometric apparatus constituting an hydraulic press and having a cylinder and a piston, means connecting the last-mentioned cylinder to the cylinder of the main press, adjustable springs, means connected with said springs for balancing the common pressure upon the piston of said dynamometric apparatus and the piston of the main press, a dial and a needle cooperating therewith for showing the stresses of the test samples, and a recording apparatus for recording the same in response to the motion of either piston.

ALBERT RENÉ ARTHUIS.
